UNITED STATES PATENT OFFICE.

WILLIAM SPENCER, OF LOTHERSDALE, ENGLAND.

KILN FOR BURNING OR CALCINING LIMESTONE.

SPECIFICATION forming part of Letters Patent No. 670,820, dated March 26, 1901.

Application filed September 7, 1900. Serial No. 29,274. (No model.)

To all whom it may concern:

Be it known that I, WILLIAM SPENCER, of Lothersdale, in the county of York, England, have invented certain new and useful Improvements in Kilns for Burning or Calcining Limestone or Like Substances, of which the following is a specification.

In connection with kilns for the burning or calcining of limestone or like substances, and especially those in which there are two or more superimposed cavities or chambers with constricted intervening passages and openings for the feeding of fuel at two or more heights or levels, I have found it desirable to supply air or other combustion-supporting gases at such elevated parts of the said kilns as will insure the thorough consumption in the upper cavity or chamber of the smoke or gases given off by the burning fuel beneath prior to its escaping at the top, thus greatly enhancing the effectiveness of the fuel and at the same time obviating all possibilities of the nuisances that are produced by dense smoke.

Figure 1 represents a sectional front elevation of a kiln for burning or calcining limestone constructed in accordance with my invention. This form of kiln is incased throughout by sheet metal. Fig. 2 represents a sectional side elevation of parts illustrated by Fig. 1. Fig. 3 represents a sectional plan on line X X of parts illustrated by Figs. 1 and 2. Figs. 4 and 5 are sectional front and side elevations of my improved kiln, showing the lower part as formed within a walled or earthen embankment, while the upper part is incased by sheet metal. Fig. 6 represents a sectional plan on line X X of parts illustrated by Figs. 4 and 5.

Similar letters of reference indicate similar parts throughout the several views.

The kilns illustrated by the accompanying drawings are typical of the class of kilns to which my invention is applicable, though it will readily be understood that it may be applied to other kilns of somewhat similar general construction, but having certain details therein of a modified formation.

In the kilns illustrated the limestone or like substance is fed through the iron doors at the opening d into the chamber or cavity

a and descends on each side of the bridge-piece c into the cavity b in order that fuel fed through the opening c' in the said bridge-piece c may be deposited in the center of the 55 said limestone or the like, in this manner causing the calcining process to be uniformly carried out. The limestone further descends through the constricted opening e into the chamber f, in the upper part of which 60 other openings g are arranged for the feeding of fuel in order that the calcining process may be completed. The calcined limestone or the like is withdrawn through the draw-holes h in the well-known manner. 65

To devise means whereby the fuel fed through the opening c' and the combustible gases resulting therefrom and also from the fuel fed in at the openings g may be effectively burned or consumed at the most desirable place within the kiln is the especial feature of my present invention. 70

To attain the object of my said invention, I form within the inner walls A of the kiln a series of vertical flues m, which lead from the 75 annular cavity n, somewhat surrounding the lower part of the kiln, (and which is common to the whole series of flues m,) to a position approaching the passage e, and at this place I make them converge into a fewer number 80 of flues o, which finally lead into the kiln, preferably through the walls of said constricted passage e. Appropriate dampers p are employed for regulating the flow or passage of the currents of air as may be found 85 necessary, an arrangement of these being illustrated by the several figures. When the chamber f is not built into or surrounded by earth, the openings r, as shown by Fig. 3, are formed to lead from various points in the flue 90 n, while when the chamber f is built into or surrounded by earth then the openings r are arranged as shown by Fig. 6. This latter formation of kiln, as will be seen, is such as to enable its production out of the old-fashioned running-kiln u. By thus constructing the series of flues m within the inner walls A of the kiln a large proportion of the surface of said walls A is thereby protected against

the fierce heat therein by an ever-changing 95 layer of air, so that the deteriorating effects thereon are greatly reduced, while the cur-

rents of air are heated to a considerable degree prior to their entrance into the kiln.

I inclose or cover the whole outer surface of the kiln as shown by Figs. 1 and 2 or the 5 upper chambers *a* and *b* in the formation of kiln shown by Figs. 4 and 5 with a casing or covering *q*, of sheet metal or the like, in order to prevent the ingress of air (which would affect the economic working of the kiln) 10 at these parts should there be any openings through the walls of the kiln, caused by a fracture of such walls or from any other cause, and to prevent a like ingress of air when following the construction shown by Figs. 4 and 15 5 I have the walls in the embankment surrounded by an appropriate thickness of fire-proof cement concrete *s*.

Within the upper sheet-metal chimney or shaft *w* I mount a damper *t*, by which the 20 draft through the kiln may be regulated or almost entirely shut off.

Such being the nature and object of my said invention, what I claim is—

1. A kiln comprising in its construction a 25 plurality of superimposed chambers with a constricted intervening passage, fuel-inlets at the upper part of each chamber, and air flues or passages in the walls of the lower chamber, said flues being adapted to supply

air to the material located in or descending 30 through the said constricted passage.

2. A kiln comprising in its construction a plurality of superimposed chambers with a constricted intervening passage, fuel-inlets at the upper part of each chamber, air flues 35 or passages in the walls of the lower chamber, said flues being adapted to supply air to the material located in or descending through the said constricted passage, and a plurality of dampers for regulating the currents of air 40 through said flues.

3. A kiln comprising in its construction a plurality of superimposed chambers with a constricted intervening passage, a bridge extending across the upper chamber and having 45 a fuel-passage therethrough, fuel-inlets at the upper part of each chamber, and air flues or passages in the walls of the lower chamber, said flues being adapted to supply air to the material located in or descending through 50 the said constricted passage.

In testimony whereof I have affixed my signature in presence of two witnesses.

WILLIAM SPENCER.
